UNITED STATES PATENT OFFICE

2,545,242

ATTACHMENT FOR DOMESTIC BOILERS

Felix P. Robinson, Cottonwood, Idaho

Application October 18, 1946, Serial No. 704,139

2 Claims. (Cl. 122—94)

1

This invention relates to attachments for fireboxes and boilers for domestic heating plants, particularly such as are usually installed for heating systems of dwellings, apartments, and large buildings, and the invention is designed to increase the heating capacity of such installations through the employment of auxiliary water circulation pipes or coils, preferably installed at the side walls of the firebox, with the ends of the coils connected to the boiler below the fire flues and to the boiler above the normal water line, so that as water is derived from the boiler and stands in the coils to the water line, the additional heating occasioned by the proximity of the coils in the firebox to the heat of the products of combustion and the expansion, due to said increased heating, causes the escape of the water at the upper end of the coil which is not obstructed by the water in the boiler, and therefore, a continuous circulation of this hot water increases the temperature of the water in the boiler and results in an economical employment of the fuel, augmenting its heating capacity, through the use of the said coils.

It is an object of this invention to provide novel means whereby the coils are connected through a wall of the firebox to the boiler and through the top wall of the firebox, the said pipe of the coil being extended so that it discharges above the water line of the boiler; and furthermore, provision is made for producing leak-proof joints between the coil and the wall of the firebox, as well as the top plate thereof; and the said device can be readily installed in equipment now in common use and has proven inexpensive to install and maintain.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 illustrates a sectional view of a conventional type of heating boiler, showing the heating coil in elevation in the firebox;

Figure 2 illustrates a sectional view of the equipment on the line 2—2 of Fig. 1; and

Figure 3 illustrates a sectional view of the boiler on the line 3—3 of Fig. 1.

In these drawings 5 denotes a conventional type of boiler having the usual fire tubes 6, smoke up-

2

take 7, firebox 8, ash pit 9, and furnace door 10, and where coal fuel is employed, a grate 11 will be used, though in modern furnaces these may be omitted and the usual liquid or gas burners substituted.

Water circulating coils 12 and 13, each comprising a number of convolutions of pipe, are installed along each of the side walls 14 of the fire box, and it is obvious that the number of convolutions may be increased or diminished, according to the size of the firebox and the diameter of the pipe employed. The lower end of each pipe projects through an aperture in the rear wall of the firebox near the bottom of the boiler and is in communication with the boiler below the fire tubes, and it is engaged on the inner side of the wall of the firebox by a flanged nut 15 threaded on the tubes so that when the flange of the nut engages the wall of the firebox, a tight joint is produced. The end 16 of the tube projects upwardly through the top plate of the firebox and terminates above the water line so that the water is free to discharge into the boiler and mix with the water in the boiler, and it will assist in raising the temperature of the water of the boiler, as will be apparent. An appropriate leak-proof joint 17 of any conventional type may be employed in assembling the pipe and top plate of the boiler.

As will be understood, the boiler construction and the attachment are so arranged structurally as to be completely cooperative in developing maximum efficiency as the water-heating agency for domestic heating systems, the boiler being operatively connected with the feed and return lines leading to and from the various room heating units (not shown) contained within the heating system. For instance, the boiler is of the horizontal type with its firebox at one end and its products of combustion flue located at the opposite end and remote from the firebox, the two zones being connected by the series of tubular flues, these extending upward toward the outlet flue at a slight angle and spaced apart sufficient to permit ready circulation of water about the tubes; the major portion of the water content is located between the firebox and the outlet flue and is of considerable extent. As thus far described, the boiler is of a general type.

However, the boiler of the invention carries several distinguishing characteristics as compared from such general type. One of these distinctions consists in the fact that the bottom of the boiler extends practically to the level of the bottom of the firebox with its top positioned a material distance above the top of the firebox,

the result being that the tubular flues are practically in the mid zone of the height of the boiler and with the depth of the water content considerably greater than that usually present in horizontal boilers—the surface level of the water content reaches into the boiler zone above the top of the firebox although such level is itself spaced from the top of the boiler. As a result, a large content volume is present, enabling a shorter boiler to be used, but it tends to restrict the tubular flue zone to an intermediate zone of the water content with resultant portions of the content depth located above and below such tubes. Since the direct heating of this body is by the tubular flues, it is essential that circulation conditions be present within such boiler portion. Generally, this condition is met by largely increasing the number of tubular flues especially in the lower zone to provide an upward circulation. However, with the number of tubes restricted in the present invention and the presence of the bodies of water above and below the tube zone, a different type of circulation is needed.

As indicated in the drawings, the latter is secured by the use of the coils 12 which are of the sinuous type and located at opposite sides of the firebox and within the firebox itself, each coil having its entrance at the bottom end of the coil and extending through the rear wall of the firebox close to the bottom of the boiler, the coil then passing sinuously in the form of connected parallel tubular portions of considerable length extending from front to rear of the firebox with the portions mainly arranged on a vertical plane adjacent the side walls of the firebox and thus in close proximity to the fire within the firebox, a location which serves to heat the content of the coil intermediate its ends with exceeding rapidity. As a result, such heated content will rapidly rise and pass out of the upper end of the coil at its upper end and at the same time cause water content from the bottom zone of the boiler to enter the lower end of the coil and provide a rapid upward circulation of water through the coil. While this circulation provides a temporary removal of water content from the boiler proper, it remains within the boiler walls and during its absence is being subject to the direct heating within the firebox itself; consequently, the water will pass through the coil at a very high rate and thereby provide a withdrawal of water from the bottom zone of the boiler and thus create a downward circulation of the water within the boiler at a material rate. While the latter effect would tend to reduce the heating effect of the flues due to a shorter period of contact, such result is not present in practice, due to the fact that the highly heated coil content is being delivered onto the top surface of the boiler content in the vicinity of the intake entrance of the cooler water returning from the heating system so that the top zone of the boiler content does not actually have the temperature of the returning water but is an admixture of the cooler returning water and the highly heated coil content, the admixture thus raising the temperature of such top zone. Hence, the water passing the zone of flues 6 during the downward circulation is of higher temperature than the returning water, with the result that less heating is required by the flue zone.

From this, it can be understood that the boiler although of comparatively large size and containing a large volume of water, does not require a large number of flues—twelve being shown—and

those present can be concentrated at an intermediate zone of the height and width of the boiler, and yet obtain many of the effects produced with boilers of the "flash" type, but without the restrictions as to volume that are typical of that type.

The construction and arrangement of parts and their function having been stated in connection with a description of the several parts, a résumé 10 of the operation of the device is believed unnecessary for an understanding of the invention by one skilled in the art.

I claim:

1. In domestic boiler assemblages for hot water 15 heating systems, the combination with a horizontally-extending boiler having a firebox in one end zone and an outlet for products of combustion in the opposite end zone, a plurality of tubular flues connecting the firebox and such opposite end zone with the flues inclined upwardly from the firebox, the diameter of the boiler being greater than the depth of the firebox with the lower zone of the boiler above the lower plane of the firebox and the boiler upper zone extending 20 above the top plane of the firebox, such upper zone extending in overlying relation to the top plane of the firebox with such latter plane positioned below the normal water level of the boiler to thereby provide open communication of water content between the main portion of the boiler and such overlying zone below such water level, the normal water level being within such boiler upper zone and spaced from the top wall of the boiler to thereby form a top space into which the 25 return flow from the heating system is delivered, of a pair of individual heating coils positioned within the firebox and adjacent the opposite side walls thereof, each coil having its lower end extending through the inner wall of the firebox and open within the lower zone of the boiler adjacent the bottom of such zone, each of the pair of coils having its opposite end zone extending through the upper wall of the firebox and having its open end above the normal water level and 30 shaped to extend toward the main portion of the boiler to thereby provide a pair of individual water conduits operative to rapidly transfer water content from the lower zone of the boiler to the space above the water level by the rapid 35 temperature rise of the water traversing the coils within the firebox to increase the rate of circulation of the water content of the main portion of the boiler and to increase the temperature value of the returning water content from the system 40 and thereby increase the rapidity of the circulation.

2. A combination as in claim 1 characterized in that each coil has the portion of its length that is located within the firebox of sinuous form 45 with a plurality of parallel horizontally extending tubular portions each of a length approaching the front to rear length of the firebox with corresponding ends of a pair of adjacent portions connected by a curved portion and with 50 said portions extending in a common vertical plane to thereby produce the sinuosity of the coil, the upper and lower portions each including an extension projecting laterally inward from such plane toward the central vertical zone of the firebox with the lower extension then extended laterally rearward for passage through the firebox rear wall adjacent the bottom of the central zone of the boiler, the upper extension then extending upwardly through the top wall of the firebox in- 55 to and through the water content of the boiler

zone above the firebox and above such level and then laterally rearward to thereby space the water discharge outlet from the coil inwardly from the adjacent side wall of the boiler.
